UNITED STATES PATENT OFFICE.

EARL K. CHANEY AND WILLIAM BROWN, OF HILLSBORO, OHIO.

INTERCHANGEABLE SHOW OR DISPLAY CASE DIVIDER.

1,116,996.

Specification of Letters Patent. Patented Nov. 10, 1914.

Application filed December 15, 1913. Serial No. 806,835.

To all whom it may concern:

Be it known that we, EARL K. CHANEY and WILLIAM BROWN, citizens of the United States, residing at Hillsboro, in the county 5 of Highland and State of Ohio, have invented certain new and useful Improvements in Interchangeable Show or Display Case Dividers; and we do declare the following to be a full, clear, and exact description of the 10 invention, such as will enable others skilled in the art to which it appertains to make and use the same.

This invention relates to improvements in adjustable supports for partitions or dividers adapted to be used in connection with 15 show or display cases of ordinary construction.

The primary object of the invention is to provide a support of this character which 20 may be adjusted longitudinally of the display case to bring the partitions supported thereby closer together or farther apart.

A secondary object is to so construct the supports as to render the partitions readily 25 removable therefrom.

With the above objects in view, the invention resides in certain novel features of construction and combination herein described and claimed, and shown in the drawings, 30 wherein:—

Figure 1 is a front elevation of a show case, parts being broken away to more clearly show the manner of applying our invention thereto. Fig. 2 is a vertical section on the line 2—2 of Fig. 1. Fig. 3 is a vertical section on the line 3—3 of Fig. 2, and Figs. 4 and 5 are detail perspective views showing the adjustable sleeves which are employed in the rear and front of the 40 display case, respectively.

In the accompanying drawings, we have shown a display case C which may be of any suitable construction and forms no part of the present invention. The doors D, at the 45 rear of the case, are slidably mounted upon the usual strip S resting upon the bottom or base B of the case. The front of the case, designated at F, is provided with the usual glass G, through which the articles within 50 the case may be viewed.

Coming now more particularly to details of the present invention, front and rear rods 1 and 2 respectively are connected by screws 3 to a wooden strip 4 in the front of the casing and the strip S at the rear of the casing. Mounted to slide upon the rods 1 and 2 are

split sleeves 5, said sleeves carrying vertical standards 6, which are provided near their lower ends with upwardly opening hooks 7.

Slides 8 are loosely mounted on the upper 60 ends of the standards 6 and said slides are provided with downwardly opening hooks 9 which co-act with the hooks 7 to retain the partitions P, in upright position. The partitions P, as clearly shown in Fig. 2, are 65 preferably, though not necessarily, notched at their four corners, the notched portions receiving the hooks 7 and 9.

The sleeves 5 and their co-acting parts, so far described, are free to move longitudinally upon the rods 1 and 2 to move the partitions P to any desired spaced relation. When the proper adjustment of the partitions is obtained, set screws 10, passing through the sleeves 5, may be tightened to 75 contact with the bar 1 or 2, as the case may be, and securely lock the sleeves in adjusted position.

By reference to the drawings, it will be seen that the sleeves 5 and the standards 6 80 are constructed in what we term rights and lefts, and by forming them in this manner, we are enabled to position the standards 6 at points nearer to the front of the casing C than would be possible were they constructed as shown in Fig. 4.

The structure above described is particularly adaptable to show cases in which cakes, nuts, candies or the like are to be displayed, and as above described, the partitions P may be adjusted longitudinally of the rods 1 and 2, or they may be entirely removed therefrom by sliding the sleeves 5 to either end of the rods 1 and 2, since said rods terminate at points spaced suitable distances from the ends of the casing C to allow the sleeves 5 to be removed. All parts are preferably, though not necessarily, of nickel plated brass and present a very neat appearance when in position within the 100 case C.

Although we have described our invention with considerable minuteness, we do not wish to be limited to details of construction other than those amplified in the appended claims.

Having thus described our invention, what we claim as new and desire to secure by Letters Patent is:—

1. The combination with a base, of a supporting rod carried thereby, a sleeve mounted to slide thereon, an arm on said sleeve

and hooks on said arm adjustable toward or away from each other.

2. The combination with a base, of a supporting rod carried thereby, a sleeve mounted to slide thereon, an arm on said sleeve, a hook and a slide on said arm and a hook on said slide, said first and second mentioned hooks opening toward each other.

3. The combination with a base, of a supporting rod carried thereby, a sleeve mounted to slide thereon, a vertical standard on said sleeve, an upwardly opening hook on said standard at its lower end, a slide on its upper end, a downwardly opening hook on said slide, and means for locking said sleeve on said rod.

4. The combination with a display case,

of longitudinal rods carried by the floor thereof, sleeves mounted to slide on said rods, vertical standards on said sleeves, upwardly opening hooks on the lower ends of said standards, slides on the upper ends thereof, downwardly opening hooks on said slides, and partitions having their upper and lower edges engaged by the hooks on 25 said slides and said standards.

In testimony whereof we have hereunto set our hands in presence of two subscribing witnesses.

EARL K. CHANEY.
WILLIAM BROWN.
